W. H. Bizer.

UNITED STATES PATENT OFFICE.

WM. H. BITZER, OF MUSCATINE, IOWA.

ARRANGEMENT OF DEVICES IN SHINGLE-MACHINES.

Specification of Letters Patent No. 25,945, dated November 1, 1859.

To all whom it may concern:

Be it known that I, W. H. BITZER, of Muscatine, in the county of Muscatine and State of Iowa, have invented a new and Improved Shingle-Machine; and I do hereby declare that the following is a full, clear, and exact description of the same, reference being had to the annexed drawings, making a part of this specification, in which—

10 Figure 1, is a side view of my invention. Fig. 2, is a horizontal section of the same, taken in the line x, x , Fig. 1. Fig. 3, is a detached view of the bolt carriage and its platform.

15 Similar letters of reference indicate corresponding parts in the several figures.

This invention relates to an improvement in that class of shingle machines in which the shingles are cut in taper form from the 20 bolt by a circular saw and at the same time planed at one side.

To enable those skilled in the art to fully understand and construct my invention I will proceed to describe it.

25 A, represents a rectangular framing on one end of which a saw arbor B, is placed, said arbor having a circular saw C, at one end. At the side of the framing A, and by the side of the saw C, a platform D, is secured, and on this platform a carriage E, is placed and fitted in a suitable 30 guide so that it may move freely back and forth in a right line. The carriage E, is operated by a connecting rod F, and crank 35 G, the latter being on one end of a shaft H, placed in the framing A, said shaft being driven by a belt I', from a drum J, on a driving shaft K. On the shaft H, a working pulley L, and an idle or loose pulley M, is placed, the belt I, being shifted from one 40 to the other as required by means of a belt shipper N. The saw arbor B, is rotated by a belt O, from the drum J.

P, is a horizontal bar which is placed in 45 the lower part of the framing A, and works on a fulcrum pin a. To the opposite end of the bar P, a vertical frame Q, is attached, and in this frame a rotary planer R, is fitted, said planer being rotated by a belt b, 50 from the shaft H.

S, is a spring which is secured in the lower part of the framing A, and bears against the bar P, said spring having a tendency to keep the planer R, in close proximity to the saw C, see Fig. 2.

On the upper surface of the carriage E,

two racks c, c, are attached, one near each side. These racks are each provided with alternate long and short teeth d, e, the long teeth of one rack being in line with the short teeth of the opposite one, as shown clearly in Fig. 2. On the carriage E, and between the two racks c, c, a bolt T, is placed, and to each side of the bolt a spring or elastic catch f, is secured. The form of these catches is clearly shown in Fig. 3. These catches act as pawls and engage with the racks c, c. In the lower part of the framing A, a lever U, is placed and secured by its fulcrum pin g. This lever is connected 70 at one end with a vertical hand lever V, which is near a hand lever W, of the belt shipper N. The opposite end of lever U, bears against the bar P, of the rotary planer frame Q.

The operation is as follows:—The bolt T, is placed on the carriage E, and the pawls or catches f, f, are placed into two corresponding sized teeth d, d, or e, e, of the racks c, c. The planer R, is then by actuating 80 lever V, thrown out from the saw C, and the face of the bolt is “squared” or sawed off to be parallel with the plane of rotation of saw C. One of the pawls or catches f is then shifted into a tooth which is out of line 85 with the tooth in which the other pawl or catch is engaged, that is to say, if one pawl is fitted in a short tooth e, the other will be fitted in a longer one d. The bolt T, is fed to the saw C, manually or by the operator, each pawl being moved forward alternately, the distance of a large and small tooth so that the bolt will be fed obliquely to the saw, the two sides of the bolt being alternately foremost so that the shingles will be 90 sawed from the bolt in taper form, the butts and thin ends being sawed alternately from opposite sides of the bolts. The rotary planer R, smooths off the shingles as they 95 are cut from the bolt and the planer is kept to its work by the spring S, the spring allowing the planer to yield or give to compensate for the taper form of the shingles. The reciprocating movement of the carriage E, may be stopped at any time by shifting 100 the belt I, on the loose or idle pulley M, and the planer R, may be thrown free from the bolt when desired by simply actuating the lever U, through the medium of lever V.

I do not claim broadly the employment or use of a circular saw and rotary planer for sawing and planing shingles, for they have 110

been previously used for similar purposes; but

I do claim as new and desire to secure by Letters Patent—

5 The arrangement of the frame Q, and planer R, upon the self adjusting swinging bar P, and the combination of the parts thus

arranged with the pivoted lever U, and reciprocating carriage F, as and for the purpose herein shown and described.

WM. H. BITZER.
